EMIL G. JEGGE, OF NEWARK, NEW JERSEY, ASSIGNOR TO E. I. DU PONT DE NEMOURS & COMPANY, OF WILMINGTON, DELAWARE, A CORPORATION OF DELAWARE.

PRESS.

Application filed April 27, 1923. Serial No. 634,982.

This invention relates to presses, more particularly of the fluid-pressure-operated, e. g. hydraulic, type and has particular relation to a press of this type having means to facilitate loading and unloading. Since the illustrated press has been advantageously used in, and is more particularly adapted to, the art of forming cakes of pyroxylin plastic from a collection of smaller individual bodies of plastic, the invention is described with more particular reference to that art; but it will of course be understood that the invention is not limited thereto.

In the manufacture of pyroxylin plastics, i. e. bodies plastic under heat and pressure and comprising nitrocellulose, camphor and liquid solvents in suitable proportions, it is desired to unite by pressure and heat individual bodies of stock into large cakes (which cakes are later sheeted to give sheet goods.) In the pressing, the stock must be supported at its sides, as well as at the top and bottom which are directly subjected to the pressure, in order to form the cake. This side support is given by the forming frame or "chase" of the press; but while a necessary part of the press the "chase" ordinarily renders loading and unloading of the press decidedly awkward as is evident, since it surrounds the charge. Furthermore, because the pressed charge adheres to the chase the freeing of the charge from the chase is difficult. The present press has means for overcoming these and various other difficulties. In brief, the press has a chase and a supporting plate which are relatively movable, in the direction of the height of the cake, whereby the chase may be moved to such a position that stock may be placed on, or removed from, the supporting plate without interference by the chase; and, also, the press has positively actuatable means for relatively moving the pressed cake and chase to positively free or "strip" the cake from the chase.

One object of the invention is to provide a press having provisions for relative movement between the charge-supporting table and the charge-confining frame.

Another object is to provide a press having positively acting means for relatively moving the charge-confining frame and the charge.

Another object is to provide a press hav-

ing provisions for facilitating loading and unloading.

Another object is to provide means for controlling the pressure-fluid feed and discharge of a fluid-pressure press.

Another object is to provide a press of the characteristics above mentioned having means for controlling the pressure-fluid feed and discharge.

To these ends, and also to improve generally upon presses and devices of the character indicated, the invention consists in the various matters hereinafter described and claimed.

The more clearly to describe, the invention, but without restricting it thereto, the same is described with more particular reference to the embodiment thereof illustrated in the accompanying drawings. In these drawings:

Figure 1 is a vertical sectional view taken substantially on the line 1—1 of Figure 2, diametrically of the cylindrical pistons, the upper portion of the press being shown, however, in elevation for simplicity, and the central portion of the series of passages for temperature controlling medium being indicated merely by dot-and-dash lines;

Figure 1^a is a fragmental enlargement and amplification of a portion of Figure 1;

Figure 2 is a horizontal section substantially on the line 2—2 of Figure 1, showing the charge supporting parts in plan with certain parts thereof in dotted lines, and the showing of the series of temperature-medium passages being simplified as in Figure 1;

Figure 3 is an end elevation of the press with the parts in loading position, with the end wall of the chase removed;

Figure 4 is a fragmental view similar to Figure 3, with the parts in pressing position;

Figure 5 is a side elevation (as in Figure 1) of the fluid-pressure-flow-controlling mechanism, partially in vertical section;

Figure 6 is an end elevation of said mechanism, and Figures 7 and 8 are, respectively, a plan view and an elevation of the piping, essentially diagrammatic in character.

Referring now to the drawings, and for the present more particularly to Figure 1, the illustrated press comprises the base 1,

the columns or supports 2, the top 3 supported by the column 2 and carrying the force plate or abutment 4, and the press plate or pressure applying member 5 which 5 fixedly carries the charge confining frame or chase 6 guided by the columns 2. The member 5 is mounted upon a piston 7 for actuation thereby, the piston 7 being reciprocatively received in the fluid cylinder 8 10 connected by the pipe 9 with a suitable source of fluid (water) under pressure and with a suitable discharge.

In accordance with the present invention, a supplemental, or stripping plate 10 is 15 received within the chase 6 for reciprocative movement with respect thereto, and this plate serves to immediately carry the charge C (conveniently supported on a cake plate 11). The stripping plate 10 is actuated by a piston 12 reciprocable in the piston 7, the latter in practical effect serving as a cylinder for the piston 12, and being what I may conveniently term a "piston-cylinder." Fluid (water) under 20 pressure is introduced to, and may escape from, the cylinder 7 by the pipe 13 communicating with the cylinder 7 below the piston 12. A clearance space 14 is provided in the recess 15 in the stripping plate 10 25 for the piston 12, by reason of which the stripping plate can seat on the press plate, clear of the piston 12. For venting the cylinder 7 above the piston 12, and also the clearance space 14, a vent passage 14^a 30 is provided in the stripping plate extending from the space 14 to the exterior of the plate, and the piston 12 has a somewhat loose fit in the press and stripping plates providing for the passage of air from the 35 cylinder to the space 14; the vent 14^a has free communication with the atmosphere when the stripping plate is raised, and, of course, when the stripping plate is in lowered position its connection with the 40 press plate is not an air-tight one, so that free communication is provided at all times. Desirably the bottom of the plate 10 is provided with strengthening ribs 10^a, and the plate 5 with grooves 5^a to receive them. 45

50 In operation, see Figures 3, 1, and 4, with the piston 7 at the bottom of its stroke, and hence with the chase in lowered position, pressure fluid is introduced through the pipe 13 whereby the piston 12 is raised 55 and the stripping plate correspondingly raised (the clearance 14 being taken up). This movement is continued until the cake plate is brought substantially to or above the top of the chase (Fig. 3). With the 60 parts in this position, the chase is in non-interfering position and the press may be readily and conveniently loaded. The loading completed, fluid is introduced at the pipe 9 and the press plate and chase raised 65 until the stripping plate seats in the press

plate ready to transmit the pressure from the press plate to the charge. (Fig. 1.) During this movement the pressure between the pistons 12 and 7 is of course relieved as required to permit the rise of the piston 7, seating of the stripping plate, and the clearing of the piston 12 from the stripping plate at 14). By continued application of the pressure below piston 7 the pressing is done (Fig. 4). Upon completion of the pressing, the pressure fluid is introduced between the pistons to force down the piston 7. The result is that while the cake is upheld by the stripping plate the chase is positively forced down, thus positively, and with a force that may be made as great as circumstances require, stripping the chase from the cake. After the stripping the pressure may be relieved to facilitate removal of the cake and the cake removed quickly and readily without interference by the (lowered) chase.

Among the various operating features of the press I particularly call attention to the positive stripping. While it might seem that a reliance upon gravity for lowering the chase might serve, the fact is that with materials such as pyroxylin plastic for example, the adherence between the chase and cake is so great that in a press of feasible size and weight gravity operation is not dependable. The present arrangement ensures positive stripping under all conditions. I also call attention to the piston arrangements whereby it is provided that the pistons, and connected parts, can be moved independently of each other to any desired position to give the exact location of chase and press plate, stripping plate, and force plate desired under various circumstances. And I also call attention to the provision of the clearance space above the stripping-plate-actuating piston whereby it is provided that when the pressing is actually being done the pressure is transmitted from the large piston, through the press plate and stripping plate to the charge, instead of being applied partly by the small piston.

For the ready and convenient control of the movements of the press by inexpert operators, a semiautomatic mechanism for controlling the flow of pressure fluid is preferably provided. Such a means is indicated generally at 16, Figure 1, (and in detail in Figures 5 to 8). In general, it comprises a plurality of valves designated generally as 17 for controlling the supply of high pressure fluid supplied by the pipe 18, and the supply of low pressure fluid supplied by the pipe 19, and means for actuating the valves in mechanically determined sequence to direct the fluids to the pipes 9 and 13, and to permit discharge from the cylinders. Such latter means is designated generally

as 20 and comprises a hand-operated shaft 21 for rotating cam discs 22 and 23 to actuate the valves 17. Detailed explanation of this mechanism appears hereinafter.

5 Conveniently to connect the fluid pipe 13 with the space 24 beneath the piston 12, the arrangement illustrated in Figure 1 may desirably be used. The pipe 13, of sufficient length to provide for the desired relative 10 movements of the press plate and stripping plate, has a sliding fit in the press plate at 25 and is so connected with one end of a channel 26 as to move with the stripping plate and maintain the connection during 15 movement, as indicated at 27. At its other end the channel communicates with a fluid pipe 28 as indicated at 29. The pipe 28 (which is fixed to the stripping plate at 30 and has a sliding fit in the piston 12, at 20 31), communicates with a channel 32 in the piston, which channel in turn communicates with the space 24 before mentioned. The pipe 13 connects with the controller 16 and may include a flexible portion 33 providing for movement with the plate 10. Thus in this way there is conveniently provided a proper connection between the controller 16 and the space 24 behind the piston 12, with provision for the relative movements of the press plate, stripping plate and stripping piston 12.

The pressing piston 7 and pressing plate 5 may desirably be connected for convenient assembly and disassembly as shown. In this 35 construction a species of "breech-block-lock" 34 is shown comprising fan-like or radial flanges 7^a, 7^b on the upper portion of the piston (Figures 1 and 2) received in corresponding recesses 5^a, 5^b provided by hook-like 40 downward extensions 5^b, 5^b on the underside of the press plate casting. The open sector-shaped spaces between the extensions 5^b are of course sufficiently wide to permit entrance of the flanges 7^a. In assembling the flanges 7^a are introduced into such spaces and the parts rotated to introduce the flanges into the recesses 5^a as will be understood. Desirably a locking pin 35 is used to lock the parts against relative rotation. It will be seen that this construction 50 provides a connection which, while easily assembled is well able to withstand and transmit the pulling and pushing forces to which it is subjected.

55 Preferably when, as in the present instance, a press embodying the invention is intended for use with material, as pyroxylin plastic, which is to be heated and cooled during treatment, the apparatus includes provisions for the circulation of temperature controlling fluid. As here illustrated the chase, forceplate, and cake plate are equipped with such provisions. They are indicated as series of pipes 36, 37 and 60 38 suitably connected as at 38^a (Fig. 2) for

flow from one pipe to the other and receiving at one end of the series and discharging at the other. As will be understood the detail arrangement of the piping may be greatly varied, the invention not being confined to any particular detailed arrangement. Desirably the temperature may be automatically controlled as by a suitable thermostatic control device preferably of the type exemplified by a Tagliabue temperature control (not shown) the details of the same forming no part of the present invention. Desirably, the provisions for conducting temperature controlling medium to and from the cake plate 11 are such that the flow channels 38 of cake plate are connected with the controlling-medium-flow passages upon placing of the cake plate upon the stripping plate, without the necessity for the manipulation of joints, couplings, or the like by the operator. To this end in the illustrated embodiment (Figure 1^a) the press plate 5 is provided with flow pipe units 39, to which the flow passages proper 40 are connected. An expanding spring 41, received in a recess 42 in the plate 5 between the bottom of the recess and a collar 39^a on the pipe unit 39, urges the unit toward the cake plate, movement being limited by the nut 43 abutting the underside of the press plate. The upper end of the unit 39 carries a nipple 44 adapted to fit tight in the mouth of a passage 45 in the cake plate and communicating with the fluid channels 38. The stripping plate is provided with a recess 46 for receiving the unit 39 as shown. In operation, it is evident that, assuming, of course, proper adjustment of the nut 43, when the cake plate is placed on the stripping plate the nipple 44 connects the flow pipe fluid tight with the passage 45 and channels 38.

Although in the illustrated embodiment the chase and immediately related parts are of shapes to give a rectangular cake, it is obvious that parts contoured to give any other desired form to the cake may be used. Also the parts may be shaped to give any called for detailed configuration to the cake. For example, as here illustrated more particularly in Figure 2, the chase may be provided with flutes 6^b which, as the stock is pressed, form ribs on the cake. When the cake is sheeted (horizontally) the ribs furnish tabs at the edges of each sheet by which the same may be hung. If desired the upper surface of the cake plate may be provided with dovetail ribs to lock the cake (as it flows during pressing) to the cake plate, so that the cake plate and cake may go to the sheeter as a unit.

Returning now to the controller 16, the detailed construction of the illustrated controller is as follows (see Figures 5 to 8) -- The mechanism provides for the intro-

duction of liquid under high pressure and liquid under low pressure to both cylinders, and for suitable discharge of the liquid. Furthermore, it provides for the control of 5 the flow in such a way that the various desired operations of the press are performed in predetermined order, all movements of the various valves being correlated to ensure the proper directing of the several flows 10 and discharges necessary to the different called for movements and positions of the elements of the press. As before stated, Figure 5 is an elevation of the controller, Figure 6 an end view, Figure 7 a plan view 15 of the piping and Figure 8 an elevation of the same. The series of valves, heretofore designated generally as 17, comprises three pairs *a*, *b*, and *c*, *d*, and *e*, *f*, the pairs *a*, *b*, and *c*, *d*, being associated in like manner 20 and comprising the spring seated valves working in chambers *a'*, *b'* and *c'* *d'* which chambers are connected by passages, *x*, *y*, as shown. The pair *e*, *f*, comprises the spring seated valves working in chambers *e'* *f'* connected by the passage *z* as shown. The various valve chambers are provided with the ports *a¹⁸*, *b⁹*, *b⁴⁷*; *c¹⁸*, *d¹⁸*, *d⁴⁷*; *e⁹*, *f¹³*, *f¹⁹*, located as indicated. The pair *a*, *b*, controls high pressure supply to, 25 and all exhaust from, the cylinder 8; the pair *c*, *d*, controls high pressure supply to, and all exhaust from, the cylinder 7; and the pair *e*, *f*, controls low pressure supply to both cylinders. As will be understood, 30 the liquid may enter the valve chambers and flow around the valves proper, the valves serving to control the flow of the liquid along the valve passages. The high pressure supply pipe 18 is connected with the 35 ports *a¹⁸* and *c¹⁸*; the pipe 9 for the large cylinder 8 connects ports *b⁹* and *e⁹*; an exhaust pipe 47 connects with the ports *b⁴⁷* and *d⁴⁷*; a connecting pipe 48 connects the port *d⁴⁸* and pipe 13; the low pressure supply pipe 19 connects with the port *f¹⁹*; and the supply pipe 13 to the small cylinder 7 connects with the port *f¹³*.

The valves are controlled and moved by the operating member 20, operated shaft 21 and the cams 22 and 23, as heretofore stated generally. In detail, the cam block 22 is provided with a pair of cam grooves 22*a*, *b* and 22*c*, *d*, and the cam block 23 is provided with a cam groove 23*e*, *f*. Associated with 55 each cam groove is a rocker arm, as 49, fulcrumed at 50 and provided with the cam follower 51 and tappets as 52^a and 52^b. The operation is evident. The cams are of course contoured to give desired sequence of 60 operations, the center lines of the grooves, to give the sequence set out below, being substantially indicated by the lines 22*a*, *b*, 22*c*, *d*, and 23*e*, *f*, in Figure 6. The operating member 20 is provided with a plurality of operating handles, as I, II, III, IV and V corre-

sponding to the various operating positions, and a spring pressed pawl 53 serves to locate the operating member in each position, the vertical position on the upper arc of swing desirably being the operating or indicating 70 position of a handle. (In Figure 6, the member 20 is shown at position III which corresponds substantially to Figures 1 and 5.)

The sequence of operations and positions of the valves is desirably as follows: V neutral, chase and stripping plate down, valve *a* closed, *b* open, *c* closed, *d* open, *e* closed and *f* closed; no inflow but communication open from both cylinders to exhaust. I (revolve wheel 20 counter-clockwise from V) 75 to raise stripping plate under low pressure to loading position, *a* closed, *b* open, *c* closed, *d* closed, *e* closed, *f* open, low pressure supplied to cylinder 7 from pipe 19 through valve *f* to pipe 18, valve *b* open to permit 80 exhaust from cylinder 8 through pipe 47. IV (revolve wheel clockwise through V) to raise chase and press with low pressure, *a* closed, *b* closed, *c* closed, *d* open, *e* open, *f* closed, low pressure supplied to cylinder 8 from pipe 19 through channel *z*, and port 85 *e⁹* and pipe 9, and exhaust open from cylinder 7 through valve *d* to pipe 47. III (revolve wheel clockwise from IV) to raise 90 chase and press with high pressure, *a* open, *b* closed, *c* closed, *d* open, *e* closed, *f* closed, high pressure supplied to cylinder 8 from pipe 18 through valve *a*, channel *x*, port *b⁹* and pipe 9. II (revolve wheel clockwise 95 from III) to force down chase and strip with high pressure, *a* closed, *b* closed, *c* open, *d* closed, *e* open, *f* closed, high pressure supplied to cylinder 7 from pipe 18 through valve *c*, channel *y*, port *d⁴⁸*, pipe 48, and pipe 13, valve *e* open to admit low pressure 100 to cylinder 8 to give a cushioning effect (total pressure in cylinder 7 being greater than that in cylinder 8) and the low pressure liquid backing up into the accumulator or escaping through a safety valve as desired and as will be understood by those skilled in the art. I (revolve clockwise from 105 II) to continue stripping with low pressure. V (revolve clockwise from I) valves *b* and *d*, being open to relieve all pressure, stripping plate sinks to lowered position. It will be noted that the use of both high and low pressure at different stages of the same operation, as noted above, provides for conservation of the relatively expensive high pressure liquid. As previously indicated, a valve does not immediately control the port opening into the chambers, but rather controls the passage below the valve body; 110 since the liquid can enter the valve chamber from the port and flow about valve. For example the ports *a¹⁸* and *b⁹* are always open (as is port *b⁴⁷*) and flow through *b⁹* from pipe 18 is determined by the valve *a*, 115 depending on whether it be "open" to per-

mit flow past it through channel x to port b^o , or is "closed"; and is also determined by the valve b , depending on whether it be "open" to permit flow past the valve body to port b^r , or is "closed."

I claim:

1. In a press, in combination, a force plate, a press plate movable toward and from the force plate, a chase fixedly carried with the 10 press plate, a stripping plate within the case and movable toward and from the force plate independently of the press plate and chase, and provisions for moving the press plate and carried chase independently 15 of the stripping plate.

2. In a press, in combination, a force plate, a press plate movable toward and from the force plate, a chase fixedly carried with the press plate, a stripping plate within 20 the chase and movable toward and from the force plate independently of the press plate and chase, and provisions for positively actuating the press plate and carried chase to move the same into charge-released position, and for maintaining the stripping plate 25 in pressing relation with said force plate, thereby to positively strip the charge from the chase.

3. In a fluid-pressure-operated press, in 30 combination, a cylinder, a piston-cylinder therein, a piston in the piston-cylinder, a press plate carried by the piston-cylinder, a chase carried by the press plate, a stripping plate carried by the piston and within said 35 chase, and means for conducting pressure fluid to and from the cylinder and the piston-cylinder.

4. In a fluid-pressure-operated press, in 40 combination, a cylinder, a piston-cylinder therein, a piston in the piston cylinder, means for individually and separately-controllably conducting pressure fluid to and from the cylinder and the piston-cylinder, and charge supporting parts carried by the 45 piston and the piston cylinder.

5. In a fluid-pressure-operated press, in combination, a cylinder, a piston-cylinder therein and having a closed bottom, a piston in the piston-cylinder, means for conducting pressure fluid to and from the cylinder, means for conducting pressure fluid to and from the piston-cylinder such means 50 communicating with said piston-cylinder between the bottom thereof and the piston, and charge supporting parts carried by the piston and the piston-cylinder.

6. In a fluid-pressure-operated press, in combination, a cylinder, a piston-cylinder therein and having a closed bottom, a piston 60 in the piston-cylinder, a press plate carried by the piston-cylinder, a chase carried by the press plate, a stripping plate carried by the piston and within said chase, means for conducting pressure fluid to and from the cylinder, and means for conducting pressure 65

fluid to and from the piston-cylinder such means communicating with said piston-cylinder between the bottom thereof and the piston.

7. In a fluid-pressure-operated press, in 70 combination, a cylinder, a piston-cylinder therein and having a closed bottom, a piston in the piston-cylinder, a press plate carried by the piston-cylinder, a chase carried by the press plate, a stripping plate carried by 75 the piston and within said chase, means for conducting pressure fluid to and from the cylinder, means for conducting pressure fluid to and from the piston-cylinder such means communicating with said piston-cylinder 80 between the bottom thereof and the piston, and pre-set means for controlling the flows of pressure fluid to and from the cylinder and the piston-cylinder to operate the press plate and chase, and the stripping 85 plate in predetermined sequence.

8. In a fluid-pressure-operated press, in 90 combination, a pair of plates, assembled for relative movement there-between, means for moving one of said plates and comprising a cylinder and received piston, and pressure-fluid-passage means for conducting fluid to the cylinder by way of said one plate while the same is moving with respect to the other, such means comprising fluid passage provisions 95 extending from the exterior of said one plate to said cylinder, and a pipe connected with the exterior end of said fluid passage provisions for movement with said one plate and slidably mounted in the other 100 plate to slide in the direction of movement.

9. In a fluid pressure-operated press, in 105 combination, a press plate and a stripping plate, means for moving the stripping plate with respect to the press plate and comprising a cylinder and received piston, and pressure-fluid-passage means for conducting fluid to the cylinder by way of the stripping plate while the same is moving with respect to the press plate, such means comprising 110 fluid passage provisions extending from the exterior of the stripping plate to said cylinder, and a pipe connected with the exterior end of said fluid passage provisions for movement with said stripping plate, and slidably mounted in the press plate to slide in the direction of movement.

10. In a fluid-pressure-operated press, in 115 combination, a press plate, a stripping plate received thereon, a cylinder, a piston-cylinder received therein and having a closed bottom and connected with said press plate to actuate the same, a piston received in said piston-cylinder and immediately connected with said stripping plate to actuate the same and means for conveying pressure fluid to the piston-cylinder behind said piston, such means comprising a fluid passage extending throughout the length of said piston, a fluid passage in said stripping plate and 120

- having one end connected with the fluid passage of said piston and its other end opening upon the exterior of such plate, and a pipe connected with said stripping plate 5 at such open end to move with said plate, said pipe extending through said press plate and being slidably mounted therein to slide in the direction of movement of the plates with respect to each other.
- 10 11. In a machine of the character indicated, in combination, a charge-shaping structure, a charge-supporting structure, a pressure abutment, and provisions for moving the two said structures with respect to each other and to said pressure abutment, such provisions including movement-controlling means for operating the said structures in predetermined sequence.
- 15 12. In a fluid-pressure-operated machine 20 of the character indicated, a charge-shaping structure, a charge supporting structure, a pressure abutment, fluid-pressure-operated means for moving the two said structures with respect to each other and to said pressure abutment, and movement controlling means for directing the flow of fluid to said first means in predetermined sequence.
13. In a fluid-pressure-operated machine 30 of the character indicated, a charge-shaping structure, a charge supporting structure, a pressure abutment, fluid-pressure-operated means for moving the two said structures with respect to each other and to said pressure abutment, and movement controlling 35 means for directing the flow of fluid to said first means in predetermined sequence, such movement controlling means including a piping system connected to the fluid-pressure-operated means, a series of valves in the 40 piping system, and means in the character of valve operating levers, cams actuating said levers, and contoured to move the valves in predetermined sequence, and means for actuating said cams.
- 45 14. The combination with a fluid-pressure-operated-press comprising a pair of cylinders and pistons to be operated in sequence for performance of the desired movement of the pressing elements, of a pressure-fluid control, such control comprising a system of piping for conducting flow to and discharges from, the cylinders, a series of valves incorporated in the piping system, and means for operating the valves in predetermined sequence giving the desired 50 movements of the pressing elements.
- 55 15. In a pressure-fluid control, for combination with a fluid-pressure-operated press 60 comprising a pair of cylinders and pistons to be operated in sequence for performance of the desired movements of the pressing elements; such control comprising a system of piping for conducting flow to and discharge from, the cylinders, a series of valves incorporated in the piping system for con-
- trolling the flows through the system, and semi-automatic means for operating the valves in predetermined sequence giving the desired movements of the pressing elements.
16. In a press, in combination, a press 70 plate, a stripping plate, an optional connection between said plates for actuation of the stripping plate by the press plate, means for moving said press plate, and means for moving said stripping plate independently 75 of said press plate, there being an optional operating connection between said stripping plate and its operating means, said two optional connections being coordinated to provide for actuation of the stripping plate by 80 the press plate during pressing.
17. In a press, in combination, a press 85 plate, a stripping plate arranged to rest on said press plate, means for moving the stripping plate independently of the press plate, means for moving the press plate, and provisions whereby during pressing, said stripping plate, resting on said press plate, is moved by said press-plate-moving 90 means and disconnected from the stripping-plate-moving means.
18. In a press, in combination, a press 95 plate, a stripping plate having a recess and arranged to rest on said press plate, means for moving the press plate and comprising 100 a pushing element having a recess in alignment with said first named recess and means for moving the stripping plate independently of the press plate and comprising a pushing element received in said recesses and means 105 whereby such element may be moved, the bottom-to-bottom distance between said recesses being less than the length of said stripping-plate-pushing element whereby 110 said stripping plate may rest on said press plate for actuation by such plate and its pushing element, free from operating connection with the stripping-plate-pushing element.
19. In a fluid-pressure-operated press, in 115 combination, a press plate, a stripping plate, there being an optional connection between said plates for actuation of the stripping plate by the press plate, a piston for moving the press plate, and a piston for moving said 120 stripping plate independently of said press plate, there being an optional operating connection between said stripping plate and its operating piston, said two optional connections being coordinated for actuation of the stripping plate by the press plate during 125 pressing.
20. In a press for treating the charge under controlled temperature and pressure, in combination, a pressure abutment, a press 130 plate, a chase carried thereby, a stripping plate received within the chase, means for moving the press plate and chase, and the stripping plate, relative to said abutment to apply pressure to the charge, and a charge-

- carrying plate received on said stripping plate, said charge-carrying plate and said chase being provided with means for the circulation of temperature controlling medium.
- 5 21. In a press for treating the charge under controlled temperature and pressure, in combination, a press plate, a stripping plate received upon said press plate and movable to and from the same, means for 10 moving the stripping plate, a charge plate carried upon said stripping plate and provided with passage means for a temperature controlling medium, and conducting means for conducting medium to said passage 15 means, such conducting means being carried by the press plate and arranged for projection through the stripping plate when the same is in immediate relation to said press plate, and for fluid tight connection 20 with said passage means.
22. In a press for treating the charge under controlled temperature and pressure, in combination, a press plate, a stripping plate received upon said press plate and 25 movable to and from the same, means for moving the stripping plate, and a charge plate to be carried upon said stripping plate and provided with passage means for a 30 temperature controlling medium, such passage means having an exterior controlling-
- medium-receiving aperture, said press plate carrying a controlling medium pipe, and said stripping plate having an aperture, said first-named aperture, said second named aperture, and said pipe being located for 35 registration.
23. In a press for treating the charge under controlled temperature and pressure, in combination, a press plate, a stripping plate received upon said press plate and 40 movable to and from the same, means for moving the stripping plate, a charge plate to be carried upon said stripping plate and provided with passage means for a temperature controlling medium, such passage means 45 having an exterior controlling-medium-receiving aperture, said press plate carrying a controlling medium pipe, and said stripping plate having an aperture, said first-named aperture, said second named 50 aperture, and said pipe being located for registration, said pipe being of a length to extend through said aperture of the stripping plate, when said press plate and stripping plate are in immediate relationship, 55 and abut the aperture of the charge plate, and means for holding said pipe in close relation with such aperture.

In testimony whereof I affix my signature.
